CLAIM

The ornamental design for a tire, as shown and described.

DESCRIPTION

FIG. 1 is a perspective view of a tire showing our new design, it being understood that the pattern repeats uniformly throughout the circumference of the tread;

FIG. 2 is a front elevational view thereof;

FIG. 3 is a right side elevational view thereof;

FIG. 4 is a the left side elevational view thereof;

FIG. 5 is an enlarged fragmentary front elevational view taken from Line 5-5 of FIG. 2; and,

FIG. 6 is a sectional view thereof taken along line 6-6 of FIG. 2.

In the drawings, the broken lines showing of the sidewall, inner bead and the peripheral boundary between the tire
